Primary Examiner — Paula Greene(74) *Attorney, Agent, or Firm* — Thorpe North & Western LLP(57) **CLAIM**

The ornamental design for loudspeaker holder, as shown and described.

DESCRIPTION

FIG. 1 is a front perspective view of a loudspeaker holder according to my new design, with the environment shown in broken lines;

FIG. 2 is a front perspective view of the loudspeaker holder of FIG. 1 without the environment;

FIG. 3 is a rear perspective view of the loudspeaker holder of FIG. 2;

FIG. 4 is a front view of the loudspeaker holder of FIG. 2;

FIG. 5 is a rear view of the loudspeaker holder of FIG. 2;

FIG. 6 is a left hand side view of the loudspeaker holder of FIG. 2, the right hand side view being a mirror image of the left hand side view;

FIG. 7 is a top plan view of the loudspeaker holder of FIG. 2; and,

FIG. 8 is a bottom view of the loudspeaker holder of FIG. 2. The broken lines form no part of the claimed design.

1 Claim, 7 Drawing Sheets
